Attorneys

UNITED STATES PATENT OFFICE

JOHN F. WILSON, OF DETROIT, MICHIGAN, ASSIGNOR TO GENERAL MOTORS CORPORATION, OF DETROIT, MICHIGAN, A CORPORATION OF DELAWARE

RADIATOR-FILLER CAP

Application filed March 2, 1929. Serial No. 344,008.

The present invention in caps, although involving elements of artistic merit, is directed particularly to utilitarian features; and it aims particularly to provide a simple and attractive cap or closure organization which includes, (1) an annular body, (2) a pivoted lid or top plate, and (3) rotative means, involving no use of threads, for easily but releasably securing said lid in a sufficiently tight relationship to said annular body,—which may be threaded to a usual or special tubular element, such as a flanged filler pipe at the top of a radiator or the like.

It is an object of this invention to provide, in a filler cap, cam means, preferably comprising a peripheral ring provided with a projecting handle, for normally securing a pivoted lid or top plate in engagement with an annular body within which said ring may be permanently but slidably seated in a manner permitting a limited rotation thereof; and, in preferred embodiments of this invention, the said body may provide a pair of oppositely facing annular depressions, interposed between cylindrical walls and adapted respectively to receive gaskets or packing elements,—one of said packing elements being adapted to engage a flange upon the top of a tubular element and the other being adapted to engage an annular projection provided upon the lower surface of the mentioned lid or plate.

Other objects of this invention, in which said lid or plate may be provided with a notched downward projection engageable by a cam surface upon the mentioned ring, and in which said ring may be so held in an annular depression by an outside collar as to permit and to limit the mentioned sliding rotative movement, for a locking and unlocking effect, and in which one of the mentioned gaskets may be supported by resilient means which tend not only to produce a tight joint but to elevate said lid upon the release of the mentioned latch, and in which said latch may be provided with means obviating unintended release thereof, may be best appreciated from the following description of an illustrative embodiment of said invention, taken in con-

nnection with the appended claims and the accompanying drawings.

Fig. 1 is a front elevational view, showing an embodiment of the invention as applied to a radiator filler pipe.

Fig. 2 is a vertical section taken substantially as indicated by the line 2—2 of Fig. 1.

Fig. 3 is a horizontal sectional view, taken substantially as indicated by the line 3—3 of Fig. 2.

Fig. 4 is a perspective view, taken substantially as indicated by arrows 4 of Figs. 2 and 3, but showing only a locking ring, as hereinafter referred to.

In that embodiment of my invention which has been selected for illustration, a filler pipe 11 is shown as provided with both an in-turned flange 12 and an externally threaded portion 13,—the latter being adapted to engage corresponding internal threads upon a body 14, shown as pivotally carrying a lid 15.

The body 14 is shown as annular in form, as provided with upstanding ears or an upstanding lug 16 through which extends a pin 17 for the pivotal connection of said lid member, and as provided with a downwardly facing annular depression 18 within which a threadless locking ring 19 may be retained by means such as an outside collar 20. In preference to threading this collar upon the cap body, it may be retained by means such as a set screw 21, the latter being shown as serving also to secure the entire cap against rotation upon the tubular member 11.

The body member 14 is shown as comprising an inner cylindrical element 22 and a horizontal web 23 so formed and proportioned as to provide oppositely facing annular channels or depressions 24 and 25, respectively adapted to receive annular gaskets 26 and 27; and said gaskets may be respectively advanced by resilient means such as annular plates 28, 29 respectively provided with series of integral and off-set spring tongues 30, 31,—the lower gasket 27 being thereby pressed into engagement with the flange 12, or its equivalent, and the upper gasket 26 being shown as normally contacting with an

annular projection 32, integral with the lid 15.

It is an incidental but important merit of the described construction that, upon the release of whatever latching means may be employed to hold the lid 15 in its closed position, the mentioned annular spring means, or any equivalent resilient means disposed beneath the gasket 26, automatically elevates the said lid to a sufficient angle to obviate the necessity for providing any handle thereon,—although not necessarily to such an angle as is suggested by dot-and-dash lines at 15', Fig. 2.

In preference to mounting any peripheral locking ring thereon, the lid 15, or its equivalent (whether ornamented or merely provided with a rounded or substantially conical upper surface, as suggested at 33), may include or carry a downward projection 34,—shown as so notched at 35 as to constitute the same a hook or latch member, to provide an interlocking engagement with a cooperating part 36 of the mentioned rotatively slidable ring 19; and said ring is shown as provided with a cam surface 37, disposed between a notch 38, through which the projection 34 may be depressed, and an ornamental handle 39. The projection 34 is shown as provided with an outwardly extending lip 40, engageable by the cams surface 37; and the ring 19 is shown as provided, directly beneath the handle 39, with a notch 41 into which the lip 40 may be permitted to snap, for a releasable interlocking effect, upon the rotation of said ring from the dotted line position shown in Fig. 3 to the full line position shown in Figs. 1, 2 and 3.

The mode of operation having been fully indicated in connection with the foregoing description, it may be noted that a notch 42 in a flange 43, which constitutes an outer wall of the peripheral depression in which the ring 19 is rotatively slidable, may be of such length as to prevent movement of the ring 19 beyond the respective positions suggested in Fig. 3; and the clearances provided thereby, as at 44, Fig. 2, should be sufficient to permit the front of said ring to be resiliently elevated, at will, to a degree sufficient for the release of the lip 40 from the notch 41.

Although the particular resilient means illustrated as advancing the respective gaskets 26 and 27 into engagement with cooperating parts might not be suitable for use upon a cap designed to withstand very high pressures, the materials and proportions herein suggested or implied have been found entirely suitable to the specific use indicated; a mere lateral shifting of the handle 39, or its equivalent, provides a simple and satisfactory means to control the position of the lid 15, with incidental tightening and loosening effects; and, if desired, as a further precaution against accidental release, the top

of the notch 41 may be inclined, for an opposite cam effect, away from the inclined surface 37,—the relationship here referred to being suggested in Fig. 1.

Although the foregoing description has included but one complete embodiment of the present invention, it should be understood not only that various features thereof might be independently employed but also that numerous modifications not suggested herein might easily be devised,—without involving the slightest from the present invention.

I claim:

1. A radiator filler cap comprising: a body member; a closure plate member pivoted thereto; a threadless locking ring member peripherally carried by one of said members and provided with means to hold the other of said members thereto,—said last mentioned member being provided with a hook and said ring member being provided with a notch through which said hook may extend and also with a cam surface adjacent said notch.

2. A radiator filler cap comprising: an annular body member; a closure plate member pivoted thereto; and a threadless peripheral cam ring member rotatively slidable upon one of said members and constituting means to engage and draw the other of said members thereto.

3. A radiator filler cap comprising: an annular body member; a closure plate member movable relatively thereto; and a threadless peripheral cam member which is rotatively slidable upon one of said members and constituting means to engage and draw the other of said members thereto,—two of said members being respectively provided with an annular depression to receive a gasket and with a corresponding annular projection to compress said gasket.

4. A radiator filler cap comprising: an annular body member; a closure plate member pivoted thereto; and a threadless peripheral cam member which is rotatively slidable upon one of said members and constitutes means to engage and draw the other of said members thereto,—said cam member being provided with a handle and said body member being provided with both an annular passage to receive said cam and a notch so shaped as to permit a limited relative movement between parts of said members.

5. A radiator filler cap comprising: an annular body member; a closure plate member pivoted thereto; and a threadless peripheral cam member which is rotatively slidable upon one of said members and constitutes means to engage and draw the other of said members thereto,—said cam member being integral with a ring, and said ring being retained, in a depression provided in said body member, by means of an outside collar.

6. A radiator filler cap comprising: an an-

nular body member; a closure plate member pivoted thereto; and a threadless peripheral cam member which is rotatively slidable upon one of said members and constitutes means to engage and draw the other of said members thereto,—said cam member being integral with a ring and being retained, in a depression provided in said body member, by means of an outside collar extending into said depression and secured by means which serve also to secure said body member upon a tubular element.

7. For use in a radiator filler cap of the general character described: a body member provided with oppositely facing depressions between cylindrical walls for the reception of gaskets, each of said depressions containing resilient means for yieldably supporting a gasket, and said depressions being defined in part by a web extending between the cylindrical walls of said body.

8. A cap organization comprising: a body member provided with an upwardly-facing annular depression adapted to contain both an annular spring and a gasket disposed thereabove; a closure plate pivoted to said body member and provided with an annular projection to engage said gasket and also with a locking projection; and cam means movable peripherally of said body and adapted to engage said locking projection and thereby to depress said plate and to compress said gasket.

9. A cap organization comprising: a body member peripherally carrying a cam member having a handle; a lid member pivoted to said body member and provided with a projection engageable, for a locking effect, by said cam member; and means operative to lift said lid member upon the disengagement of said projection by said cam member.

10. A cap organization comprising: a lid member; a body member provided with a downwardly-facing annular depression adapted to receive a gasket and with an internal threaded portion therebelow; and a tubular element provided with a flange opposite said depression and with an external thread therebelow,—a gasket having an annular spring element thereabove being disposed in said depression.

In testimony whereof I affix my signature.

JOHN F. WILSON.
